PORTABLE PAINT AND LIQUID MIXER

Arthur P. Jorgenson, Racine, Wis., assignor, by
mesne assignments, to Landon P. Smith, Inc.,
Irvington, N. J., a corporation of New Jersey

Application February 1, 1937, Serial No. 123,439

3 Claims. (Cl. 259—108)

This invention relates to devices for stirring, mixing, or blending paint or other liquids by direct action upon such paint or liquid in a container.

5 The invention resides in a form of apparatus in which an electric motor, or other suitable source of power, is provided with rigid baffle supports which bear opposing baffles at their ends and in which the rotating shaft of said motor 10 or power source connects with a shaft disposed between the baffle supports, upon which shaft is carried an impeller or impellers. The motor drives the shaft in the proper direction to throw a liquid which is to be treated against the faces 15 of the opposing baffles. The whole is arranged for ready portability and, by reason of the fact that the reaction of the impeller is largely absorbed by the baffles, may be provided with simple and effective clamping means for securing 20 the same to the side of a container, preferably in such manner that the baffles forming the lowermost part of the apparatus may rest directly upon the bottom of the container.

Portable agitators for the mixing of paint or 25 other fluids have been constructed in a wide variety of forms. In the forms heretofore proposed or used, however, the principal object sought apparently has been to produce circulation in the liquid undergoing treatment. For the 30 redisposition of badly caked or settled-out paint the object to be sought is not so much that of circulation of the liquid, but rather that of the grinding or disintegration of the solid aggregates which are loosened or washed away from the 35 cake by the circulating fluid. Heretofore such an action has been obtained only in large stationary equipment and it has been the custom to return to the factory where such facilities are available paint which has become badly caked through 40 protracted storage. In the apparatus of this invention, however, a simple and easily portable and easily cleaned apparatus is provided which produces, in addition to an active circulation of the fluid, an impact disintegration of aggregates 45 suspended therein.

The apparatus of this invention is best described by reference to the accompanying drawings, wherein—

Fig. 1 is a side view of an apparatus of this 50 invention, shown mounted in position in a typical container, portions of the latter being broken away;

Fig. 2 is a fragmentary end view of a part of the apparatus shown in Fig. 1;

55 Fig. 3 is a section, looking upwardly, of the

apparatus shown in Fig. 1, taken at the plane 3—3;

Fig. 4 is a section taken downwardly of the apparatus shown in Fig. 1, taken at the plane 4—4;

Fig. 5 is a sectional view, looking downwardly, taken at the plane 5—5 of Fig. 1, showing in detail the construction of an auxiliary impeller; and

Fig. 6 is a side view in detail of the impeller shown in Fig. 5.

Referring to Fig. 1, there is shown one form of apparatus embodying this invention. The apparatus there shown comprises a motor 1, for furnishing power for operation thereof. The motor may be of any suitable type, as, for example, a one-fourth H. P. single phase induction motor, capable of operating upon ordinary commercially distributed electric power. Secured to the top of the motor 1 is a convenient grip handle 2 in which there is housed a suitable switch 3 for starting and stopping the motor. As shown more clearly in Fig. 2, the grip handle 2 is secured to the motor by means of bolts 4. A flexible cable 5 is provided through which the necessary driving current is supplied.

Rigidly secured to the bottom of the motor 1 is a supporting frame 6, which is held in place by bolts 7, as shown more clearly in Fig. 1. The frame 6 for all intents and purposes is a rigid portion of the housing of the motor 1 and may be integrally formed therewith, if desired. Formed as a part of the frame 6 are sockets 8 in which are held the square baffle supports 9. The baffle supports are elongated, square rods, the ends of which are diagonally slotted to receive obliquely 35 placed baffle plates 10, as shown in Fig. 1 and in greater detail in Fig. 4.

Slidably mounted upon one of the baffle support rods 9 is the mounting clamp 11, which is provided with a suitable clamping screw 12 to which there is attached a handle 13. The clamp is shown in Fig. 1 in position on the side of a typical container 15. To provide the sliding connection with baffle support rod 9, the clamp is provided with an integrally formed head 14 through which a square hole passes and in which the square rod 9 is slidably received, as is shown clearly on the right-hand side of Fig. 3. This arrangement, particularly in view of the peculiar interior configuration of the clamp 11, as shown in Fig. 1, permits the apparatus to be clamped to the rim of a variety of heights, sizes, and forms, of containers. The clamp 11 insures retention of the apparatus in a vertical position,

while the weight of the apparatus is borne directly by the bottom of the container upon which rests the lower ends of the baffles 10.

The moving parts of the apparatus are attached directly to the shaft of the motor 1, although supplementary bearings may be provided, if desired, and are composed of a coupling 16 and an elongated square impeller shaft 17. The shaft 17 bears at its lower end an impeller 18, which is mounted in a slot cut diagonally across the end of said shaft 17. The length of shaft 17 is so adjusted that the lower edge of the impeller 18 is slightly above the lower ends of the baffle plates 10, so that the rotating parts will clear the surface upon which the apparatus rests.

In addition to the impeller 18 there is positioned on the shaft 17 an auxiliary impeller 19, which is composed of a pair of blades 20 and 21 secured to a tubular hub 22. Referring to Fig. 1, it will be noted that the square shaft 17 is provided with a plurality of notches 23 disposed along its length. An inwardly projecting lug on the upper edge of the blade 20 is arranged to be received in the notches 23 when turned to the position shown in Fig. 5. Due to the shape of the notches 23 and the direction of rotation of the shaft 17, the lug on blade 20 is engaged in the notch 23, thus holding the auxiliary impeller 19 securely in place while the apparatus is in operation. If it is desired to move the auxiliary impeller to one of the other notches 23, this may be accomplished by turning the impeller 19 one-eighth of a turn clockwise, as viewed in Fig. 5, whereupon the impeller 19 may be shifted vertically to any of the other positions desired and again engaged in a notch 23. Adjustability of the auxiliary impeller 19 is desirable by reason of the variation in sizes of containers which may be employed to hold the paint or liquid undergoing treatment. Paint being treated in a one gallon container would call for an appropriately lower position of the impeller than paint undergoing treatment in a five gallon container approximating in dimensions the one shown in Fig. 1, while some containers may call for shifting the impeller 19 to the topmost notch where it is removed entirely from contact with the liquid.

In operation, the shaft 17 and impellers attached thereto rotate in the direction shown by the arrow in Fig. 4. In so doing it will be noted that the impeller 18 sweeps in a direction which may be defined by pointing out that it first crosses a line connecting the remote edges 24 of the baffles 10 and then in passing outwardly in its path it crosses a line connecting the near edges 25 of the baffles 10. The parts are arranged in relatively close proximity to one another and the impeller 18 is driven preferably at a speed of approximately 1000 to 2000 R. P. M. Under these conditions any lumps or fragments of caked or settled paint which come into the path of the impeller 18 are struck a blow of high intensity or are driven against the baffles with great force, sufficient to disintegrate and redisperse them. In accomplishing this action the baffles appear to play an important part and, preferably, should be placed obliquely, as shown, since in an apparatus not including such baffles very markedly inferior results are obtained. The baffles further play an important part in absorbing a large part of the reaction of the impeller, thus relieving the support of the heavy torque which would otherwise be imposed thereon and making possible the use of the simple sliding clamp 11 for support.

In a typical instance of use of the apparatus of this invention, five gallons of paint, held in a container similar to the one shown in Fig. 1 and designated by the numeral 15 and which has been held in storage until badly settled, is opened. An almost solid layer of appreciable depth will be found in the bottom of the container. The apparatus of this invention is thrust into the container and the clamp 11 adjusted to the rim of the container and clamped in place by means of the handle 13 on the clamping screw 12. The lower parts of the apparatus, including the baffles 10 and the impeller 18, will then be found to be resting upon, or partially penetrating, the solid layer held in the container. The apparatus is then connected to a source of electric power and the switch 3 thrown to close the circuit. Shaft 17 and the impellers carried thereby are immediately placed in rotation and the apparatus, by reason of the sliding connection with the head 20 14 of the clamp 11, immediately starts to descend, quickly reaching a position in the lower part of the container, as shown in Fig. 1. Unless the paint is unusually obstinate, after operation for approximately two minutes the entire contents of the container will be found to be uniformly dispersed. In particularly obstinate cases the handle 13 may be loosened and the apparatus moved once or twice during the treatment.

The apparatus of this invention, as will be observed from the above description, in addition to being novel is simple, convenient in use, and highly effective. Its simple construction lends itself well to rapid and easy cleaning, an important feature in any device of this nature. While this invention has been described with the aid of drawings and description setting forth one specific embodiment thereof and the manner of its use, it is intended that the protection to be granted hereon be not unnecessarily limited thereby, but that such protection extend to the full limits of the advance disclosed and claimed herein.

That which I claim as my invention and wish to secure by Letters Patent is as follows:

1. In an apparatus for mixing fluids, the combination comprising a frame, stationary baffle supports extending from said frame, baffle blades at the end of said supports disposed in planes parallel to one another and arranged obliquely with respect to a line between them, a shaft arranged for rotation and disposed lengthwise between said supports, an impeller mounted on said shaft with the faces thereof longitudinally disposed with respect to said shaft, and means engaging said shaft for rotation of the same in such direction with respect to said baffles that said impeller sweeps, during a part of its circular movement, from alignment with the exterior of the edges of said baffles to alignment with the interior edges thereof.

2. In an apparatus for fluid mixing, the combination comprising a clamp for engaging a liquid container, a vertically disposed guiding member mounted on said clamp, a rotatable impeller shaft having an impeller, a frame for rotatably mounting said shaft, and a vertical baffle support extending downwardly from said frame to a point below said impeller and being slidably held in said vertically disposed guiding member whereby said frame, rotatable impeller shaft and baffle support are held in vertical position while remaining free to rest upon and settle through a solid deposit on the bottom of said liquid container.

3. In an apparatus for fluid mixing, the combination comprising a clamp for engaging a liquid

5 container, a vertically disposed guiding member mounted on said clamp, a rotatable impeller shaft having an impeller, a frame for rotatably mounting said shaft, and vertical baffle supports extending downwardly from said frame to a point below said impeller, one of said baffle supports being slidably held in said vertically disposed

guiding member whereby said frame, rotatable impeller shaft and baffle support are held in vertical position while remaining free to rest upon and settle through a solid deposit on the bottom of said liquid container.

5 ARTHUR P. JORGENSEN.
